UNITED STATES PATENT OFFICE.

HENRY BOUNDS CARY, OF LOS ANGELES, CALIFORNIA, ASSIGNOR TO
FREDERICK W. BRAUN, OF SAME PLACE.

GASOLENE-BURNER.

SPECIFICATION forming part of Letters Patent No. 665,670, dated January 8, 1901.

Application filed January 4, 1900. Serial No. 379. (No model.)

To all whom it may concern:

Be it known that I, HENRY BOUNDS CARY, a citizen of the United States, residing at Los Angeles, in the county of Los Angeles and 5 State of California, have invented a new and useful Improvement in Gasolene-Burners, of which the following is a specification.

My invention relates more particularly to an appliance for generating the vapors in 10 starting the burner into operation. Said generator is applicable to various forms of burner, but is especially adapted for use with a form of burner known as an "open" Bunsen burner and for which I have filed an application for 15 Letters Patent of the United States, Serial No. 715,237, filed May 1, 1899, and in which a generating-chamber is provided at the end of the burner opposite the jet-piece and a pipe leads from the generating-chamber to supply the 20 jet-piece.

An object of my invention is to provide convenient and thoroughly-effective means for quickly and readily generating the vapor for starting the burner into operation.

Another object of my invention is to provide 25 for readily igniting the vapors in the generator from the flame from the burner, and vice versa.

The accompanying drawings illustrate my 30 invention.

Figure I is a perspective view of my improved gasolene-burner. Fig. II is a side elevation in longitudinal section on line II II, Fig. III. Fig. III is a front elevation of the 35 burner. Fig. IV is a cross-section on line IV IV, Fig. II. Fig. V is a fragmental plan view to illustrate the front end of the generating-shell.

a indicates the generating-chamber.

b indicates the body of the burner proper 40 for which this invention is more especially designed to be used.

c indicates the pipe leading from the generating-chamber for supplying gasolene or 45 vapor to the main burner jet-piece *d*.

e indicates an auxiliary jet-piece connected 50 with the jet-pipe *c* and arranged to direct a jet along beneath said pipe.

f indicates a shell arranged beneath the pipe 55 to inclose the jet and provided with air-inlets *g g'* and extending toward the generating-

chamber and provided near such chamber with an outlet *h* for the flame and with an imperforate mixer-section *h'* between the air-inlets and the outlet *h*. Preferably the shell 55 is in the form of a trough, and the openings are above the bottom of the trough, and the trough extends underneath the generating-chamber.

i indicates the gasolene-supply pipe, which 60 opens into the generating-chamber. *j* indicates the valve for controlling the same.

In practical use to start the burner into operation gasolene will be turned on through the supply-pipe *i* and will flow into the generating-chamber *a* and thence into the jet-pipe *c* and to the auxiliary jet-piece *e*, which will then be opened to allow the gasolene to flow out beneath the jet-pipe *e*. This gasolene will be caught in the trough *f* and will there be 70 ignited by the operator. The flame rising from the trough will heat the jet-pipe and the gasolene therein and will thereby produce the inflammable vapor, which then flows through the auxiliary jet-piece *e* and through the duct inside the shell or trough *f* beneath the jet-pipe *c*. At first while the pressure is low and the hydrocarbon vapor is practically undiluted with air it will issue at and can be ignited at the air-inlets *g g'* and will burn all along the 75 jet-pipe above the openings of the shell, thus to quickly heat the jet-pipe; but as the tension of the vapor increases the velocity of the jet will carry it through the shell and air will be entrained at the openings *g g'* and 80 will be carried into the imperforate mixer-section *h'* of the shell, where it will become mixed with the hydrocarbon vapor. The mixture of air and hydrocarbon vapor formed in the mixer-section *h'* of the shell will be of 85 a proper richness of hydrocarbon to ignite as it issues at *h* and will there produce a flame to heat the generating-chamber *a*, as well as the end of the jet-pipe *c*. When the vapor has been brought to a sufficiently high tension, 90 the main jet-piece *d* will be opened and the vapor-jet will be blown through the body of the burner, and when it issues at the farther end of the burner it will be ignited by the flame from the auxiliary jet, and the burner 95 will then come into perfect operation. The auxiliary jet may then be cut off; but so long 100

as the main jet is ignited the auxiliary jet may be ignited at any time by simply opening the auxiliary jet-valve *k*. The trough formed by the shell *f* being open at the front 5 end, as indicated, and extending beneath the generating-chamber conducts the inflammable vapors to the front of the generating-chamber, thus to be ignited by the flame from the burner. The generator-jet will thus be 10 ignited whenever it is turned on while the burner is in operation. In case the tension of the vapor should become too low at any 15 time the auxiliary jet will be turned on and its flame used to produce a required heat for the generator.

m indicates a clamp by which the shell *f* is detachably attached to the jet-pipe *c*.

What I claim, and desire to secure by Letters Patent of the United States, is—

20 1. In a gasoline-burner, the combination of a generating-chamber; a main jet-piece; a pipe communicating between the generating-chamber and the main jet-piece; an auxiliary jet-piece connected with said pipe and 25 arranged to direct an auxiliary jet along beneath said pipe; and a shell arranged beneath the pipe to inclose the auxiliary jet and provided with air-inlets and extending toward the generating-chamber and provided 30 near such chamber with an outlet for the flame and with an imperforate mixer-section between the outlet and the air-inlets.

2. In a gasoline-burner, the combination with the generating-chamber, main jet-piece and a pipe leading from the generator to the 35 main jet-piece, of an auxiliary jet-piece arranged to direct a flame along beneath said pipe; and a shell forming a trough extending along beneath the pipe and provided above its bottom with air-inlets and open at 40 the end opposite the auxiliary jet to form an outlet for the flame and being provided with an imperforate mixer-section between the air-inlet and the flame-outlet.

3. In a gasoline-burner, the combination 45 with a main jet-piece and a pipe for supplying a jet of vapor to the main jet-piece; of an auxiliary jet-piece connected with said pipe and arranged to direct a jet of gasoline or vapor along beneath the pipe; a shell arranged beneath the pipe to inclose the jet and provided at intervals with inlets to admit air, and with an outlet at the end opposite the auxiliary jet-piece and an imperforate mixer-section between the air-inlets and 50 the outlet.

In testimony whereof I have signed my name to this specification, in the presence of two subscribing witnesses, at Los Angeles, California, this 28th day of December, 1899. 55

HENRY BOUNDS CARY.
